AUTOMATIC FARE BOX

Oscar Miller, Denver, Colo., assignor of forty
per cent to Foster Cline, Denver, Colo.

Application March 5, 1932. Serial No. 597,041

13 Claims. (Cl. 235—32)

This invention relates to a coin receiving and recording device, commonly known as a "fare box", and while more particularly applicable as a fare box for street railways and the like, it will be found valuable wherever it is desired to collect and register a fare or admission fee.

The principal object of the invention is to provide a fare box which will operate entirely from the weight of the inserted coins and which will require no manual or electrical operations.

Another object is to provide a fare box which will stop and display each individual coin so that counterfeits can be detected; which will automatically separate the various coins and tokens according to their size; and which will automatically register each coin of each kind passing through the machine.

Another object is to provide means for preventing unauthorized or accidental operation of the recording mechanism.

Still another object is to so construct the fare box that it will operate efficiently regardless of the number or rapidity with which the coins are inserted.

A further object is to provide a fare box which can be completely locked within its enclosing case by means of a single seal so that unauthorized interference will be prevented, and yet so that the interior can be quickly and easily reached for repairs, renewals and the like.

A still further object resides in a novel means for securing the fare box to its supporting stand so that it can be quickly and easily removed and exchanged when necessary.

Other objects and advantages reside in the detail construction of the invention, which is designed for simplicity, economy, and efficiency. These will become more apparent from the following description.

In the following detailed description of the invention reference is had to the accompanying drawings which form a part thereof. Like numerals refer to like parts in all views of the drawings and throughout the description.

In the drawings:

Fig. 1 is a perspective view illustrating the complete device in place upon its supporting stand.

Fig. 2 is a bottom view of the improved fare box.

Fig. 3 is a perspective view of the internal mechanism with the outer housing removed.

Fig. 4 is a detail perspective view illustrating the cash drawer employed in the device.

Fig. 5 is a detail section taken through the

supporting stand on the line 5—5, Fig. 6, with the box in place thereon.

Fig. 6 is a detail view illustrating the supporting stand for receiving and carrying the fare box.

Fig. 7 is an enlarged vertical section through 60 the upper portion of the improved fare box taken on the center line A—A of Fig. 1, illustrating the coin displaying mechanism.

Fig. 8 is a detail face view of the coin receiving chute.

Figs. 9 and 10 are cross sections through the receiving chute taken on the lines 9—9, and 10—10, respectively, Fig. 8.

Fig. 11 is a plan view of the upper portion of the coin displaying mechanism with the en- 70 closing housing removed.

Fig. 12 is a continuation of the vertical section of Fig. 7 along the center line A—A of Fig. 1, illustrating the coin distributing mechanism.

Fig. 13 is a vertical section taken on the line 75 13—13, Fig. 12, illustrating a rear view of the coin distributing mechanism.

Figs. 14, 15, and 16 are plan views of the upper, intermediate, and lower coin distributing plates, respectively.

Fig. 17 is a continuation of the vertical sections of Figs. 7 and 12 along the center line A—A, illustrating the coin counting mechanism.

Fig. 18 is a rear elevation of the coin counting mechanism with its rear plate removed, look- 85 ing in the direction of the arrow 18, Fig. 17.

Fig. 19 is a front elevation of the counting wheels with the front plate of the counting mechanism removed.

Fig. 20 is a detail view illustrating the construction of the ratchet frames on the counting wheel shafts.

The entire mechanism is supported on and constructed about an internal supporting frame 20 which fits snugly within an enclosing housing 21. The front of the enclosing housing 21 is closed by means of a removable cover plate 22. A coin receiving chute 23 is secured to the front of the upper portion of the frame 20, having a coin channel 50 terminating at its upper extrem- 100 ity in a coin receiver 24.

In assembling the device, the entire frame 20 with its associated mechanism is slid within the housing 21, and moved upwardly therein until the coin receiver 24 projects through a suitable opening in the top thereof, as shown in Fig. 1. The frame is supported in its elevated position in the housing 21, by means of a cash box 25 which is slid into the housing 21 beneath the bottom of the frame 20 so as to support the lat- 110

ter. When the cover plate 22 is in place it prevents withdrawal of the cash box 25 or the frame 20.

The cover plate 22 is held in place by a top 5 flange 26 which projects under the metal of the housing 21, and by means of suitable ears 27, see Fig. 17, which project into the mechanism to receive a locking bolt 28. A front plate 29 and side plates 31 enclose the lower portion 10 of the frame 20. The front plate 29 is provided with suitable slots 30 into which the ears 27 pass. The side plates 31 are provided with openings 32 through which the locking bolt 28 passes into the ears 27. Therefore when the 15 locking bolt 28 is in place, removal of the cover plate 22 or any part of the mechanism is prevented. This bolt may be sealed as to prevent unauthorized removal thereof by means of a suitable seal 33.

20 The entire housing 21 is designed to be attached to a bracket plate 34 which is secured to any suitable supporting super-structure 35. An elongated slot 34' is formed in the bracket plate 34 to receive a slideable, round-headed, bolt 36, the lower extremity of which is provided with a wing nut 37. Two short studs 38 also project above the bracket plate 34. The bottom of the housing 21 is formed as shown in Fig. 2 with a keyhole slot 39, for receiving the head of the 30 bolt 36, and with holes 40 for receiving the studs 38.

When the housing 21 is placed upon the plate 34, the head of the bolt 36 is pushed into the enlarged portion of the slot 39. The bolt is then 35 slid forwardly into the narrow portion of the slot 39 and the nut 37 is tightened. This firmly clamps the housing over the studs 38 but allows it to be quickly and easily removed. It will be noted that the bracket plate 34 supports a coin 40 tray 41, in which the coins are caught after being removed from the cash box 25.

The coin receiving chute 23 is arranged to momentarily hold and display each coin in the rear of a display opening 42, across which suitable bars 43 are placed to prevent the coins from falling therethrough. A magnifying lens 99 is placed in the housing 21 immediately in front of the opening 42, through which a magnified image of the coin may be viewed.

50 The mechanism for stopping each coin in the opening 42 is illustrated in Fig. 7. It comprises an upper lever shaft 44 and a lower lever shaft 45. A coin actuated lever 46 projects forwardly from the upper lever shaft 44 through a vertical slot 47 formed in the coin channel 50 of the coin chute 23. The weight of each coin as inserted carries the lever 46 downwardly to the broken line position B, Fig. 7, so as to rotate the upper lever shaft 44. A stop pin 48 projects forwardly from a short lever 49 on the lever shaft 44, through suitable openings, across the coin channel 50 so that as the lever shaft 44 rotates forwardly, the stop pin 48 will be projected into the coin channel to prevent additional coins from 60 following the first until the lever 46 has returned to receive them.

The movements of the shaft 44 are communicated to the lower lever shaft 45 through a connecting rod 51 and a relatively longer lever 52 on 70 the shaft 45. The latter shaft is provided with a double lever 53, from the extremities of which, stop pins 54 and 55 project forwardly into the coin channel 50 immediately above and below the coin position in the opening 42. The above 75 mechanism is maintained in its normal position

with the lever 46 raised by means of a weight 56 which is carried on a rearwardly extending weight arm 57 from the lower lever shaft 45.

When in the normal position, the lower stop pin 55 will project across the coin channel so as 80 to support a coin at the opening 42 for inspection. When the next coin is dropped into the coin channel, it will swing the lever 46 so as to cause the mechanism to withdraw the stop pin 55 allowing the coin on display to drop, and 85 will project the upper stop pin 54 so as to support the next coin until the stop pin 55 returns it to its former position for receiving it.

Thus, if a series of coins are dropped into the coin receiver 24, each coin will actuate the lever 90 46 so as to cause the stop pin 55 to release the proceeding coin and to cause the pins 48 and 54 to hold back the succeeding coins until the mechanism is ready to receive them.

It will be noted that the front wall of the coin channel 50 is indented forwardly as shown at 58. This is to accommodate the initial movement of the stop pin 48. That is, the stop pin will start its forward movement before the coin has passed it and the pin will push the coin forward into 100 the depression 58 as the coin moves downwardly so that the pin will be in a position to stop the next above coin even before the last coin has left. This is an important feature, as it allows the stop pin to hold back and separate a continuous series of contacting coins in the coin channel so that the coins will fall one at a time to the display opening 42.

From the coin receiving chute 23, the coins pass to a distributing and separating device which 110 is shown more in detail in Figs. 12, 13, 14, 15, and 16. The separating device comprises a series of inclined plates. As illustrated the inclined plates comprise an upper coin plate 59, for the largest coins; an intermediate coin plate 60, for 115 the medium sized coins; a lower coin plate 61, for the smallest coins; and a cover plate 62. The coin plates 59, 60, and 61 each terminate in discharge spouts 63, 64, and 65, respectively. The plates are maintained in spaced relation by 120 means of suitable spacer blocks 66 and are secured together and to the frame 20 by clamp screws 67.

It will be noted that the coin chute 23 terminates at its lower extremity in a pair of rearwardly curved feet 68 which extend between the upper coin plate 59 and the cover plate 62. On the inner edges of each of the feet 68 a ledge or shelf 69 is formed which supports the largest coins or tokens by their edges and directs them 125 onto the upper coin plate 59. These largest coins will then be directed by means of coin guides 70 to the discharge spout 63.

The smaller coins will pass through an opening 71 in the upper coin plate 59 onto the intermediate coin plate 60. It will be noted that the coin plate 60 has a elongated opening 72 of slightly less width than the medium sized coin. This prevents the medium sized coins or tokens from 130 passing through and they will be guided by suitable guides 73 across the intermediate plate 60 to the discharge spout 64.

The still smaller coins or tokens will fall through the opening 72 to the lower coin plate 61 where they will be guided by coin guides 74 to 135 the discharge spout 65. Therefore each of the discharge spouts 63, 64, and 65 will independently deliver the large, medium, and small sized coins or tokens, respectively, from the spouts. The coins pass from the spouts 63, 64 and 65 respec- 140 150

tively, into vertical coin passages 75, 76 and 77, respectively in the counting and recording portion of the device which is illustrated in detail in Figs. 17 to 20.

5 The counting mechanism is located in the lower portion of the frame 20 in a compartment enclosed by the plates 29 and 31. In the front of the compartment, three series of counting wheels 78 are mounted upon three horizontal counter shafts 79, 10 there being one series of counter wheels for each of the coin passages 75, 76, and 77. Since each coin passage and its counter wheels operate similarly to the other coin passages and their counter wheels, the mechanism will be described 15 as applied to the single coin passage 75.

A ten-tooth ratchet wheel 80 is secured on the counter shaft 79 within a rotatable ratchet frame 81. A spring actuated pawl 82 is mounted in the ratchet frame 81 to engage the teeth of the 20 ratchet 80 so that, as the ratchet frame is rocked, it will rotate the counter shaft 79 in one direction. Return rotation of the counter shaft 79 is prevented by means of a second ratchet wheel 100 on the shaft 79, against which a fixed 25 spring actuated pawl 101 acts. The ratchet frame is rocked by means of a counting lever 83 which extends rearwardly across the coin channel 75 through a vertical slot 84. Thus, as 30 each coin drops down the channel, it will strike the end of the lever 83 and swing it downward to the broken line position "C", Fig. 17, so as to rock the ratchet frame and advance the counter shaft $\frac{1}{10}$ of a revolution. After the passage of 35 each coin, the counting lever 83 will be returned to its former top position by means of a coil spring 85 which is wrapped about the counter shaft 79 and acts against the ratchet frame 81.

Each of the series of counting wheels 78 is of course provided with the usual decimal shaft 36 40 for converting each complete rotation of one counter wheel into a $\frac{1}{10}$ revolution of the next as is usual in constructions of this nature.

It is of course desirable to prevent more than one coin from acting on the lever 83 at a time. 45 This is accomplished by means of a stop rod 87, which is hinged to the top of the ratchet frame 81 as shown at 88, and which projects into an opening in the inner wall of the coin channel 75 immediately above the vertical slot 84. It can be 50 readily seen that as the counting lever 83 moves downwardly, the stop rod 87 will be projected rearwardly so as to prevent other coins from passing down the channel 75 until the counting lever 83 has returned to receive them.

55 It will be noted that the coin channels widen immediately in front of the stop rod 87 so as to accommodate the initial movement of the rod similarly to the depression 58 previously described with reference to the receiving chute 23. 60 The indications on the counter wheels 78 are visible through a glass plate 89 in the front of the housing 21.

In some installations, vibration might tend to 65 swing the counting levers 83 and produce a false indication on the counting wheel. To prevent this, locking latches 90 may be pivotally mounted on the rear wall of the coin channels. The latches 90 terminate in beveled feet 91 under each of the counting levers 83 so as to lock them in the upper portions of their slots 84. The latches 90 are released by means of a short coin contact lever 92 which extends into the coin channels to contact with the passing coins. The feet 91 are maintained in the locking position by means of a suitable coin spring 93. It

can be seen that coin in passing downward in the coin channel will strike with contact lever 92 and cause it to swing the foot 91 outwardly and rearwardly so as to release the counting lever 83. It will be noted that the feet 91 are inclined so as to allow the levers 83 to ratchet pass them when returning to their former positions.

From the coin channels 75, 76, and 77 the coins fall against a bell 94 positioned in the cash box 25. To facilitate the sound of the bell reaching the exterior, suitable openings 95 are formed in the cash box which register with similar openings 96 in the housing 21. The bottom of the cash box is inclined as shown in Figs. 4 and 5 to place the coins within reach of the operator's hand when it is inserted through a pair of spring actuated doors 97.

It is desired to call attention to the forked extremity 48 formed on the stop rod 48 and a similar forked extremity 87' formed on one of the stop rods 87. These particular forked extremities are for handling tokens having an open center such as are commonly employed on street railway systems. On such tokens a single stop rod 100 would pass through the open center of the tokens as the contact levers 46 or 87 started downward so as to prevent them following the levers and effectively clogging the machine. With a forked extremity, however, the outer two points of the 105 fork contact with the edge of an open center coin and prevent the center point from passing through the opening.

It will be noted that the ratchet frame 81 of one of the series of counter wheels is secured to 110 a yoke 98 passing over the counter wheels. This is simply for the purpose of positioning the counter lever 83 and the stop rod 87 of this set in the center of the machine.

While the machine has been described for separating, counting, and registering three different types of coins, it is of course conceivable that it could be constructed to handle any desired number of different coins by simply increasing or decreasing the number of plates in the coin 120 separator, the number of channels in the counting mechanism, and the number of sets of counting wheels.

While a specific form of the improvement has been described and illustrated herein, it is desired to be understood that the same may be varied, within the scope of the appended claims, without departing from the spirit of the invention.

Having thus described the invention, what is 130 claimed and desired secured by Letters Patent is:—

1. A fare box comprising: a coin receiving and registering mechanism; a housing for enclosing said mechanism; a cash box supporting said mechanism in said housing; a front plate closing said housing and maintaining said mechanism and said cash box in place therein; locking means passing through said housing and said mechanism for locking said front plate in 140 place thereon; and ears projecting inwardly from said front plate into said mechanism to engage said locking means to lock said front plate in place.

2. Means for attaching a fare box to a supporting structure comprising: a bracket plate; studs projecting upward from said bracket plate into said fare box so as to prevent horizontal movement of the latter; and a headed bolt projecting thru a slotted opening in said 150

- bracket plate and arranged to enter a key-hole slot in said fare box and clamp in the narrowed portion of the latter to lock said fare box on said studs.
5. Means for attaching a fare box to a supporting structure comprising: a bracket plate; studs projecting upward from said bracket plate into said fare box so as to prevent horizontal movement of the latter; a headed bolt projecting thru a slotted opening in said bracket plate and arranged to enter a key-hole slot in said fare box and clamp in the narrowed portion of the latter to lock said fare box on said studs; and a coin tray formed on said bracket plate and arranged to project forward of said fare box when the latter is in position on said bracket plate. 80
6. Means for separating incoming coins in a coin box comprising: a substantially vertical coin chute having a coin passage therein; a lever pivoted adjacent said chute and projecting into said coin passage so as to be moved downwardly by the weight of a coin therein; means for returning said lever upwardly after the passage of said coin; and a stop member arranged to be projected into said coin channel in consequence of the operation of said lever to prevent succeeding coins from following the first until said lever returns; there being a depression in said coin channel opposite said stop member so as to allow the lowermost coin of a pile of coins to be moved aside by said stop member so that said stop member may engage and hold the next-above coin. 85
7. Means for registering the number of coins passing through a fare box comprising: a gravity operated coin passage; a counting wheel shaft; counting wheels mounted on said shaft; a ratchet wheel mounted on said shaft; a ratchet frame arranged to pivot about said shaft adjacent said ratchet wheel; a pawl carried by said frame and arranged to engage said ratchet wheel; and a lever projecting from said frame into said coin passage so that the weight of a coin therein will swing said lever and operate said counting wheels. 90
8. Means for registering the number of coins passing through a fare box comprising: a gravity operated coin passage; a counting wheel shaft; counting wheels mounted on said shaft; a ratchet wheel mounted on said shaft; a ratchet frame arranged to pivot about said shaft adjacent said ratchet wheel; a pawl carried by said frame and arranged to engage said ratchet wheel; a lever projecting from said frame into said coin passage so that the weight of a coin therein will swing said lever and operate said counting wheels; means for returning said lever to its normal position after it is released by said coin; and a stop rod hinged to said ratchet frame and arranged to be projected into said coin passage above said lever so that the latter operates so as to prevent succeeding coins from reaching said lever until the latter has been returned to its normal position. 95
9. Means for registering the number of coins passing through a fare box comprising: a vertical coin passage having a vertical slot in its walls; a lever pivoted adjacent said passage and projecting through said passage in said slot so as to be moved downwardly therein by the weight of a coin; a counting mechanism actuated by said lever; means for returning said lever upwardly; a stop member to be projected, in consequence of the movement of said lever, into said coin channel above said lever so as to stop the coins in said channel until said lever has returned; and a forked extremity formed on said stop member so that the extremities of said fork will contact with said coins on opposite sides of the center thereof. 100
10. Means for registering the number of coins passing through a fare box comprising: a vertical coin passage having a vertical slot in its walls; a lever pivoted adjacent said passage and projecting through said passage in said slot so as to be moved downwardly therein by the weight of a coin; a counting mechanism actuated by said lever; means for returning said lever upwardly; a stop member to be projected, in consequence of the movement of said lever, into said coin channel above said lever so as to stop the coins in said channel until said lever has returned; and a depression formed in the wall of said passage opposite said stop member so that the latter can push a coin to the side of said passage out of alignment with the next above coin. 105
11. Means for separating incoming coins in a coin device comprising: a substantially vertical coin chute; a relatively long lever pivoted at its one extremity and extending at its other extremity through said coin chute, there being a vertical slot in said coin chute to allow said other extremity to be swung downwardly by contact with the first coin moving downwardly in said chute; a short lever fixed to said long lever and 110
12. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 115
13. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 120
14. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 125
15. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 130
16. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 135
17. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 140
18. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 145
19. Means for separating coins of various sizes in a fare box comprising: a first inclined plate provided with an opening of slightly less width than the largest coin to be separated; means for directing the coins across said opening so that all except the largest will fall therethrough; a second inclined plate below said first plate for receiving the coins passing through said opening, said second plate having an opening of slightly less width than the next largest coins; means for directing the coins across the opening in said second plate so that coins smaller than the said next largest will fall therethrough; a third inclined plate below said second plate for receiving the coins passing through the opening in said second plate; a first spout positioned adjacent the middle of the lowermost edge of one plate; individual spouts for the other plates 150

- extending upwardly from adjacent the pivoted extremity thereof; a stop member hinged at its one extremity to said short lever, and having its other extremity extended toward said coin chute 5 so that as said long lever swings downwardly the latter extremity of said stop member will be projected into said coin chute to prevent succeeding coins from following the first until said lever returns.
- 10 12. Means for separating incoming coins in a coin device comprising: a substantially vertical coin chute; a relatively long lever pivoted at its one extremity and extending at its other extremity through said coin chute, there being a vertical slot in said coin chute to allow said other extremity to be swung downwardly by contact with the first coin moving downwardly in said chute; a short lever fixed to said long lever and extending upwardly from adjacent the pivoted 15 extremity thereof; a stop member hinged at its one extremity to said short lever, and having its other extremity slidably supported in an opening in said coin chute so that as said long lever swings downwardly the latter extremity of said 20 25 30 35 40 45 50 55 60 65 70 75 80 85 90 95 100 105 110 115 120 125 130 135 140 145 150
stop member will be projected into said chute to prevent succeeding coins from following the first until said lever returns.
13. Means for interrupting and separating a stream of incoming coins in a substantially vertical coin chute comprising: a substantially vertical double lever positioned opposite one face of said chute and pivoted intermediate its extremities; an upper stop pin hinged at its one extremity to the upper extremity of said lever; a lower stop pin hinged at its one extremity to the lower extremity of said lever, the other extremity of each of said pins being slidably supported in said coin chute; a relatively long lever pivoted at its one extremity above said double lever with its free extremity extending into said coin chute so as to be operated by contact with the coins therein; and a connecting rod operatively connected between said long lever and said double lever so that movement of the coins in said chute will swing said double lever to alternately project said upper and lower pins into said chute to interrupt and separate the coins therein.
- OSCAR MILLER.
